UNITED STATES PATENT OFFICE

90,473

DESIGN FOR A COMBINATION LIQUID FUEL RESERVOIR AND SUPPORT THEREFOR

William T. Bradbury, Kankakee, Ill., assignor to
Florence Stove Company, Boston, Mass., a Cor-
poration of Massachusetts

Application May 17, 1933. Serial No. 48,151

Term of patent 3½ years

To all whom it may concern:

Be it known that I, WILLIAM T. BRADBURY, a citizen of the United States, residing at Kankakee, in the county of Kankakee and State of Illinois, have invented a new, original, and ornamental Design for a Combination Liquid Fuel Reservoir and Support Therefor, of which the following is a specification, reference being had to the accompanying drawing forming part hereof.

The figure is a perspective view of a combination liquid fuel reservoir and support therefor embodying my design.

I claim:

The ornamental design for a combination liquid fuel reservoir and support therefor, substantially as shown.

WILLIAM T. BRADBURY.
